(57) **CLAIM**

The ornamental design for an electric fan, as shown and described.

DESCRIPTION

FIG. 1 is a perspective view.

FIG. 2 is a front view.

FIG. 3 is a rear view.

FIG. 4 is a right view, which is the mirror image of the left view.

FIG. 5 is a top view; and,

FIG. 6 is a bottom view.

In all figures, all parts rendered in dashed line illustrate portions of the electric fan and are not part of the claimed design.
